STEAM GENERATING UNIT

Max H. Kuhner, Oakham, Mass., assignor to Riley Stoker Corporation, Worcester, Mass., a corporation of Massachusetts

Filed Oct. 19, 1961, Ser. No. 146,123

4 Claims. (Cl. 122—235)

This invention relates to a steam generating apparatus and more particularly to apparatus arranged to produce steam for the generation of electrical power or the like.

In the design of steam generating units and, particularly, of those in an intermediate range from, say, 75,000 to 200,000 lbs. per hour, one of the drawbacks encountered is that these units are quite expensive because each unit requires an individual custom design. Furthermore, in order to obtain complete combustion of the fuel before the products of combustion pass over the convection surfaces, it has been necessary to provide an extremely large combustion chamber. In addition, extremely large buildings have been required to maintain such boilers; in many cases the fact that the burners are on different levels means that access can be had to the burners only by the operator climbing on catwalks or the like. These and other difficulties have been experienced by the prior art devices and have been obviated in a novel manner by the present invention.

It is, therefore, an outstanding object of the invention to provide a steam generating unit of the intermediate range of sizes in which the longitudinal design may remain the same for the entire range and the capacity of the unit may be increased for a specific application merely by making the furnace wider.

Another object of this invention is the provision of a compact steam generating unit which is inexpensive to manufacture for a given capacity and which requires a relatively small combustion chamber.

A further object of the present invention is the provision of a steam generating unit for use in the intermediate range of capacity in which combustion is completed well before the products of combustion pass into the convection passes.

Another object of the invention is the provision of an intermediate range steam generating unit in which the back passes and the main combustion chamber are shaped to fit together geometrically to provide an inexpensive, compact unit.

With these and other objects in view, as will be apparent to those skilled in the art, the invention resides in the combination of parts set forth in the specification and covered by the claims appended hereto.

The character of the invention, however, may be best understood by reference to one of its structural forms as illustrated by the accompanying drawing in which:

The single figure shows a longitudinal, vertical, sectional view of a steam generating unit embodying the principles of the present invention.

The steam generating unit, indicated generally by the reference numeral 10, is shown mounted in association with the operating floor 11 of a building in which the unit is housed. The unit consists generally of a boiler 12 and a furnace 13 which are inter-related in the usual manner. The furnace 13 consists generally of a front wall 14, a rear wall 15, side walls 16, a bottom wall 17, and a roof wall 18 defining a vertically-elongated combustion chamber 19. The boiler 12 consists of an upper steam-and-water drum 21 and a lower mud drum 22 which is parallel with and spaced from the drum 21. A number of down-comer tubes 23 extend from the drum 21 to the drum 22 on the rearward side of a vertical baffle 24 which extends vertically downwardly from the bottom of the drum 21. Forwardly of the baffle 24 a number of riser tubes 25 connect the drum 22 to the drum 21. A large down-comer

2

tube 26 connects the mud drum 22 to a header 27 which underlies the rear portion of the bottom wall 17 and is parallel to and spaced downwardly from the drums 21 and 22. A number of water-wall tubes 28 extend from the header 27 up the back rear wall 15 and enter the steam-and-water drum 21. Other water-wall tubes 29 extend from the header 27 along the bottom wall 17 up the front wall 14 and over the undersurface of the roof wall 18 to enter the steam-and-water drum 21. Under each side wall 16 is located a longitudinal header 31 which is connected to the mud drum 22 by a downcomer 32. From each header 31 extend water-wall tubes 33 which lie along the surface of the side walls 16 and discharge into a header 34 located above the roof wall 18, which header is also connected to the steam-and-water drum 21. A front wall 14 extends vertically upwardly from the bottom wall 17 for a short distance and then merges into a downwardly-facing, upwardly-and-inwardly inclined portion 35 which merges with an upper vertical portion 36. This portion 35 extends upwardly until it meets the roof wall 18. The rear wall 15 also extends vertically upwardly the same short distance above the bottom wall 17 and is then provided with a downwardly-facing, upwardly-and-forwardly inclined portion 37 which merges at its upper portion with an upper vertical portion 38. The upper part of the rear wall 15 has the refractory removed and the water-wall tubes 28 are bent longitudinally to provide a gas off-take 39. The space between the vertical downwardly-depend- ing baffle 24 and the upwardly-extending rear wall 15 pro- 30 vides a convection pass 41 which contains a convection superheater 42. One end of this superheater is attached to the top of the steam-and-water drum 21 and the other end is connected to the superheated steam header 43 which lies above the roof wall 18. A gas-reversal passage 44 lies between the lower end of the baffle 24 and the upper 35 surface of the mud drum 22 and another gas-reversal pas- 40 sage 45 underlies the mud drum 22 and lies within an ash hopper 46 whose forward wall is formed by the inclined portion 37 of the rear wall 15 and is provided with another inclined wall 47 located rearwardly of the mud drum. The upper edge of the inclined wall 47 of the ash hopper merges with a vertical back wall 48 which defines with the baffle 24 a back pass 49 in which most of the downcomer tubes 23 reside. A series of baffles 51 extend from the 45 baffle 24 and the rear wall 48 to cause sinuous flow of gas over the bundle of downcomer tubes. Rearwardly of the steam-and-water drum 21 the gases flow up the back pass 49 over a damper 52 to a breaching 53 for disposal. The bottom of the ash hopper 47 is provided with a ver- 50 tical slot 53 leading downwardly to a horizontal longitudinal passage 54 from which a number of nozzles 55 lead through the bottom portion of the rear wall 15 into the combustion chamber 19. A motor-driven fan 56 dis- 55 charges air at high velocity into the passage 54 and into the nozzles 55. Extending upwardly into the hopper and into the gas passage 45 is a duct 57 having a damper 58 whose setting in the duct 57 is controlled by a manually-operated rod 59. Mounted on the inclined portion 35 of the front wall 14 is a burner 61 which is of the inter-tube directional-flame type shown and described in the patent of Craig No. 2,853,059 having a central fuel gun 62 which receives fuel from a duct 63. The burner is provided with a gas-electric ignition gun 64 and is provided with a housing 65 which receives air from a duct 66 connected at 60 its other end to a forced draft fan 67 and provided with an air-flow damper 68. The burner has upper vanes 69 mounted on horizontal axes and adjustable as to inclina- 65 tion to the horizontal by means of a control rod 71. Below the fuel gun 62 the burner is provided with lower vanes 72 also mounted for adjustment about horizontal axes by means of a control rod 73. The fuel gun 62 is shown of the type having an outer pulverized-coal burner

which receives its fuel from the fuel duct 63 and an inner gas gun 74 which receives its fuel from a gas pipe 75. It will be understood that although only one burner 61 is shown on the inclined portion 35 of the front wall, that any number of burners may be used and that their operating portions and areas are readily accessible from the operating floor 11. The bottom wall 17 is provided with a slag opening 76 which is lined with water cooling pipe 77. Under the opening 76 is hung a slag tank 78 having a pool 79 of water and at its bottom a screw-type ash conveyor 81. Water injection pipes 82 and 83 are located at the upper part of the tank 78 and are provided with nozzles for spraying a continuous stream of water across the tank in the path of the downwardly-falling molten slag. The inclined portions 35 and 37 of the front wall 14 and rear wall 15, respectively, define with the bottom wall 17 a high-temperature lower cell or combustion chamber 84, while the vertical portion 36 of the front wall 14 and the vertical portion 38 of the rear wall 15 serve to define a narrow upper combustion chamber 85.

It will be understood that a plurality of burners 61 will usually be provided transversely of the furnace on the inclined surface 35 of the front wall; there also is a plurality of the injection nozzles 55 along the lower portion of the rear wall 15. The slot 53 from the hopper extends the full width of the furnace, as does the hopper itself and the recirculating gas duct 57 with its damper. A plurality of injection air fans 56 may also be used.

The operation of the apparatus will now be readily understood in view of the above description. The drum 21 operates in the usual way with water leaving the steam-and-water drum through the downcomers 23 to flow into the mud drum 22. The water flows from the mud drum through the downcomers 26 and 32 into the headers 27 and 31. From that point the water rises through the water-wall tubes 28, 29, and 33 and, eventually, the mixture of steam and water flows into the steam-and-water drum 21 where the steam moves to the top and the water circulates again. The steam passes through the superheater 42 into the superheated steam header 43 and is eventually used in a turbine or other steam equipment. The operation of the furnace is also in the usual manner; air from the forced-draft fan 67 flows into the burner 61 and into the furnace over the vanes 69 and 72 whose angles have been set by use of the actuating handles 71 and 73, respectively. Fuel enters the system through the duct 63 and the pulverized coal gun 62 as well as through the gas pipe 75 and the gas gun 74. The air and fuel mix in the combustion chamber and are ignited and maintained in ignition by the ignition gun 64. The rapidly-burning fuel and air mixture is directed by the vanes 69 and 72 downwardly toward the bottom wall 17 of the furnace. The burning mixture is then reversed, moves under the inclined portion 37 of the rear wall (which portion acts in the nature of a rear arch), and then moves vertically upwardly into the upper combustion chamber 85. It can be seen that the upper combustion chamber 85 is quite narrow compared to the lower combustion chamber 84 and, therefore, there is a tendency for the products of combustion to linger in the lower combustion chamber which, because of the high rate of heat release, becomes very hot and forms a high-temperature cell. The exit from the high-temperature lower combustion chamber 84 is, of course, the passage between the closest adjacent portions of the inclined portion 35 of the front wall and the inclined portion 37 of the rear wall. Heat transfer to the water tubes takes place mainly by radiation in the entire combustion chamber 19. The products of combustion pass from the combustion chamber rearwardly through the gas off-take 39 into the convection pass 41 where it comes into heat transfer relationship to the superheater 42 and to the riser tubes 25. The gases pass downwardly through the convection pass 41 and pass around the mud drum 22. Some of them pass above the mud drum in the passage 44 and some move down

5 through the hopper 46 in the passage 45. In either case, they are reversed and move upwardly through the back pass 49 in a sinuous flow brought about by the baffles 51. During the reversal in the passages 44 and 45 a considerable amount of the ash in the gases is thrown by centrifugal force into the hopper 46 where it slides down the outer surface of the inclined portion 37 of the rear wall and the inner surface of the inclined wall 47, these making up the walls of the hopper. The ash passes downwardly through the slot 53 into the passage 54 where it meets the air blast from the fan 56 and is thrown by the ejector principle into the nozzle 55 and into the high-temperature lower combustion chamber 84. The flyash which is in this way introduced into the furnace again contains a considerable amount of unburned combustible which is now burned; the non-combustible is melted into slag by the high average temperature existing in this high-temperature cell. All of the slag formed in the high-temperature cell flows onto the inner surface of the bottom wall 17 and eventually flows through the slag opening 76 where it is cooled by the spray from the pipes 82 and 83 and falls into the pool 79 in the slag tank 78. Eventually, it is removed from the bottom of the slag tank by the conveyor 81. It is advantageous, of course, not only to burn out the combustible left in the ash which accumulates in the hopper 46 but also this is a convenient way of disposing of the ash itself, since, as solidified slag, it is extremely concentrated in form, easy to transport and disposed of, and is saleable for use in the paving of roads and similar uses.

It may be desirable at times to regulate the temperature of steam reaching the superheated steam header 43. For this purpose, it is possible to recirculate a portion of the products of combustion. By a proper setting of the damper 58 in the duct 57, the ejector action of the air from the fan 56 passing over the bottom of the duct 57 will cause products of combustion to be drawn from the back passes of the furnace and to be thrown with the ash through the nozzle 55 into the high-temperature cell. The location of the upper end of the duct 57 is selected so that the gas drawn into the duct will be relatively free of ash; for instance, it might be located behind the mud drum 22. In any case, small amounts of flyash returned to the furnace by the gas recirculation duct are not harmful and will be disposed of in the same manner as the rest of the ash from the hopper 46. The recirculated gas, however, flows from the nozzle 55 up along the inclined portion 37 of the rear wall 15. From there it moves up along the rear wall 15, being forced into that position by the flame from the burner 61. The gas recirculated in this manner serves two purposes. First of all, it increases the mass flow of gas which flows out of the gas off-take 39 and down the convection pass 41 over the superheater 42, thus increasing the temperature of gas which flows from the superheater into the superheated steam header 43. The gas thus recirculated is also cooler than the gas from the flame and serves as an inert cooling blanket along the back wall, so that the flame from the burner 61 as it reverses itself and moves upwardly along the inclined surface 37 and the upper vertical portion 38 of the rear wall is maintained some distance away from the rear wall by the blanket of recirculated gas. This prevents the water-wall tubes and refractory from becoming too hot and also prevents the formation of slag deposits on these walls, tending to keep the walls clean and free of slag.

Manipulation of the control rods 71 and 73 permits changing the angles of the vanes 69 and 72 not only relative to their horizontal positions but also relative to one another, so that complete control of the flame in the high-temperature lower combustion chamber is permitted. Since the high-temperature cell brings about very complete combustion of the fuel, the gases which enter the upper combustion chamber 85 tend to be inert and the temperature gradient from side 16 to side 16 of the unit is quite even. It is necessary, therefore, to provide only

a small upper combustion chamber 85 since room for combustion is not necessary. Furthermore, this present construction provides for small distance from the front wall 14 to the rear wall 15 in the upper combustion chamber as is evident in the drawings. This permits a higher rate of transfer from the fuel to the water-wall tubes, since radiant transfer from a given particle is inversely proportional to the square of the distance from the particle to the surface in question. The need for a large combustion chamber is thus obviated, resulting in a much less expensive steam generating unit. At the same time, the fact that the inclined portion 37 of the rear wall not only serves as part of the high-temperature lower combustion chamber 84 but also as the bottom of the hopper 46 provides a geometric inter-relationship of the parts which provides a compact steam generating unit, thus requiring a relatively small supporting structure and building for the housing of the unit.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent, is:

1. A steam generating unit, comprising a boiler having a steam-and-water drum, a furnace having front, rear, side, roof, and bottom walls defining a combustion chamber, a header parallel to the said drum underlying the floor wall of the chamber, water-wall tubes extending from the header over the floor wall, over the front wall, and along the roof wall to the steam-and-water drum, water-wall tubes extending from the header over the rear wall to the drum, the front wall having a downwardly-facing inclined portion adjacent the floor wall, the rear wall having a downwardly-facing inclined portion adjacent the floor wall, a rear housing wall defining with the said rear wall a back pass enclosing the said heat exchanger, the lower part of the said rear housing wall being inclined to the vertical and lying in opposition to the said inclined portion forming a V-shaped ash hopper which underlies the drum, the said inclined portions serving to define a high-temperature lower combustion chamber with the floor wall, the inclined portions of the front and rear walls extending toward one another, these walls having vertical portions extending upwardly from the upper parts of the inclined portions to provide a relatively narrow upper combustion chamber, a gas off-take through the rear wall adjacent the roof wall, a convection heat exchanger section connected to and underlying the said drum, the said section lying adjacent the vertical portion of the rear wall and lying over the said inclined portion, and at least one burner mounted on the said inclined surface of the front wall.

2. A steam generating unit, comprising a boiler having a steam-and-water drum, a furnace having front, rear, side, roof, and bottom walls defining a combustion chamber, a header parallel to the said drum underlying the floor wall of the chamber, water-wall tubes extending from the header over the floor wall, over the front wall, and along the roof wall to the steam-and-water drum, water-wall tubes extending from the header over the rear wall to the drum, the front wall having a downwardly-facing inclined portion adjacent the floor wall, the rear wall having a downwardly-facing inclined portion adjacent the floor wall, a rear housing wall defining with the said rear wall a back pass enclosing the said heat exchanger, the lower part of the said rear housing wall being inclined to the vertical and lying in opposition to the said inclined portion forming a V-shaped ash hopper which underlies the drum, the said inclined portions serving to define a high-temperature lower combustion chamber with the floor wall, the inclined portions of the front and rear walls extending toward one another, these walls having vertical

portions extending upwardly from the upper parts of the inclined portions to provide a relatively narrow upper combustion chamber, a gas off-take through the rear wall adjacent the roof wall, a convection heat exchanger section connected to and underlying the said drum, the said section including a superheater lying adjacent the vertical portion of the rear wall and lying over the said inclined portion and receiving downwardly-flowing gas from the said off-take, and at least one burner mounted on the said inclined surface of the front wall.

3. A steam generating unit, comprising a boiler having a steam-and-water drum, a furnace having front, rear, side, roof, and bottom walls defining a combustion chamber, a header parallel to the said drum underlying the floor wall of the chamber, water-wall tubes extending from the header over the floor wall, over the front wall, and along the roof wall to the steam-and-water drum, water-wall tubes extending from the header over the rear wall to the drum, the front wall having a downwardly-facing inclined portion adjacent the floor wall, the rear wall having a downwardly-facing inclined portion adjacent the floor wall, a rear housing wall defining with the said rear wall a back pass enclosing the said heat exchanger, the lower part of the said rear housing wall being inclined to the vertical and lying in opposition to the said inclined portion forming a V-shaped ash hopper which underlies the drum, the said inclined portions serving to define a high-temperature lower combustion chamber with the floor wall, the inclined portions of the front and rear walls extending toward one another, these walls having vertical portions extending upwardly from the upper parts of the inclined portions to provide a relatively narrow upper combustion chamber, a gas off-take through the rear wall adjacent the roof wall, a convection heat exchanger section connected to and underlying the said drum, the said section lying adjacent the vertical portion of the rear wall and lying over the said inclined portion, and at least one burner mounted on the said inclined surface of the front wall, the burner including a fuel gun and air-directing vanes mounted for pivotal adjustment about horizontal axes, there being no burners on the inclined surface of the rear wall.

4. A steam generating unit, comprising a boiler having a steam-and-water drum, a furnace having front, rear, side, roof, and bottom walls defining a combustion chamber, a mud drum underlying and spaced from the steam-and-water drum, downcomer tubes connecting the two drums, a transverse header underlying the floor wall of the chamber, water-wall tubes extending from the header over the floor wall, over the front wall, and along the roof wall to the steam-and-water drum, water-wall tubes extending from the header over the rear wall to the mud drum, the front wall having a downwardly-facing inclined portion adjacent the floor wall, the rear wall having a downwardly-facing inclined portion adjacent the floor wall, a rear housing wall defining with the said rear wall a back pass enclosing the said heat exchanger, the lower part of the said rear housing wall being inclined to the vertical and lying in opposition to the said inclined portion of the rear wall, the said lower part and the said inclined portion forming a V-shaped ash hopper which underlies the drum, the said inclined portions serving to define a high-temperature cell with the floor wall, and a directional flame burner mounted on the said surface of the front wall.
